HAMMER FOR REMOVING DENTS FROM
THE INSIDE OF CYLINDRICAL METAL
CONTAINERSEugene Dixon, 18 Bayswater Road,
Quincy, Mass. 02169

Filed Nov. 3, 1966, Ser. No. 4,539

Term of patent 14 years

(Cl. D93—4)

FIG. 1 is an elevational view of a hammer for removing dents from the inside of cylindrical metal containers embodying my invention;

FIG. 2 is a top plan view of the hammer for removing dents from the inside of cylindrical metal containers illustrated in FIG. 1; and

FIG. 3 is a bottom plan view of the hammer for removing dents from the inside of cylindrical metal containers illustrated in FIG. 1.

The half of the hammer for removing dents from the inside of cylindrical metal containers opposite that shown in FIG. 1 is identical thereto.

I claim:

The ornamental design for a hammer for removing dents from the inside of cylindrical metal containers, as shown and described.
